UNITED STATES PATENT OFFICE.

NORMAN C. HARRIS, OF POULTNEY, VERMONT.

HOISTING AND TRAVERSING APPARATUS.

SPECIFICATION forming part of Letters Patent No. 393,643, dated November 27, 1888.

Application filed January 6, 1888. Serial No. 259,992. (No model.)

To all whom it may concern:

Be it known that I, NORMAN C. HARRIS, of Poultney, in the county of Rutland and State of Vermont, have invented a new and useful Improvement in Hoisting and Traversing Apparatus, of which the following is a specification.

My invention relates to apparatus which is employed where it is desired to raise a weight, as from a mine-shaft, and then to traverse or move the raised weight laterally for any desired distance to the place where it is to be deposited.

The invention will be hereinafter particularly described, and pointed out in the claims.

In the accompanying drawings, Figure 1 is a side elevation of an apparatus embodying my invention, showing the carriage as in traversing position. Fig. 2 is a similar side elevation of a portion of the apparatus, showing the carriage as held in hoisting position. Fig. 3 is an end view of the wheeled carriage and appurtenances, looking toward the right hand of Figs. 1 and 2. Fig. 4 is a side view of a portion of the roadway and a catch for holding the carriage in position after its traversing movement, and Fig. 5 is a transverse section of the roadway and an end view of a stop which is applied thereto and with which a hook upon the wheeled carriage engages to hold the carriage in hoisting position.

Similar letters of reference designate corresponding parts in all the figures.

A designates an elevated roadway, which is formed by a rod or wire cable, and which is here represented as inclined.

B designates a carriage, which is provided with wheels B', whereby it is supported upon the roadway A, and which is adapted to be traversed along the roadway A from end to end thereof.

As best shown in Fig. 3, the carriage B consists of two side frames or portions secured together by bolts or stretchers b and straddling the roadway A, and the wheels B', which are journaled in the side frames of the carriage B, are circumferentially grooved, so as to fit upon the roadway and to run smoothly along the same.

C designates a hoisting and traversing cable, which, as here represented, is secured at one

end, c, to the wheeled carriage, thence passes over a pulley, C', upon the wheeled carriage, and a pulley, C², which is in stationary bearings beyond the end of the traversing movement of the carriage, and is then carried downward to a hoisting-drum, C³, upon which it is wound. A bight, C⁴, of this hoisting cable depends from the carriage between the point c and the pulley C', and in this bight of cable is hung a hoisting-pulley, C⁴, which is journaled in the frame C⁵, to which is attached the hook c' or equivalent device, from which the weight to be raised is suspended. The frame C⁵ has an upwardly-extending stirrup or bail, C⁶, for a purpose hereinafter described, and which, as the hoisting-pulley is raised, passes into a guiding-funnel, B², for a purpose hereinafter described.

I have shown the carriage B in Fig. 2 as arranged in hoisting position, and it is obvious that if it be held against lengthwise movement on the roadway A the winding up of the hoisting-cable C will lift the hoisting-pulley C⁴ and elevate the weight desired to be lifted. To hold the carriage B in hoisting position, I have represented a hook, D, thereon, which is pivoted at d, and which is adapted to engage a stirrup or stop, E, upon the roadway. As here represented, the stirrup or stop E is held in position lengthwise of the roadway A by a two-part clamp, E', which may be fixed in rigid position to said roadway, and upon which I have represented heads or disks e as swiveled at e'. These heads or disks e have the stirrup or stop E rigidly fixed to them, and they are swiveled at e' upon the clamp E', or around the roadway, so that no matter what the position of the clamp upon the cable or other roadway, A, the disks or heads e will always turn 90° freely thereon and permit the stop or stirrup E to be returned by gravity to the position shown in the drawings.

If the stirrup or stop E were made a rigid part of the clamp E', the possible twisting of a cable, if one be used for the elevated roadway, would move the stirrup or stop E in a direction around such cable and would not retain it always in proper position for the engagement of the hook D with it. When, however, the stirrup or stop E is swiveled at e' upon the clamp E' or on the roadway, the stirrup or stop

will always gravitate to its lowest position and will be in the proper position for the engagement of the hook D. I have also shown in the carriage B a hook, D', pivoted at d', and which may be swung into and out of engagement with the stirrup or hanger C⁶, extending upward from the hoisting-pulley frame. D² designates a cam, which, as here shown, serves to operate both hooks, D and D'. This cam D² is fulcrumed at d² and is connected with the hooks D and D'. As here represented, the cam is connected with the hook D by a pin, d², upon the hook entering a curved slot, d¹, in the cam, and it is connected with the hook D' by a pin, d², on the hook entering a curved slot, d¹, in the cam. In fact, the hooks D D' bear against curved surfaces on the cam. The cam D² is guided in its turning movements upon the pivot d², and is also limited in its movement by a stop-pin, d³, received in a slot, d⁴, which is formed in the cam. The cam slots d¹ d⁴ are of such shape, as shown in the drawings, that when the cam is swung from the position shown in Fig. 2 to the position shown in Fig. 25, the hook D will be lowered and the hook D' will be swung into operative position across the funnel-shaped guide B³; and when the cam is swung down from the position shown in Fig. 1 to the position shown in Fig. 2 the hooks 30 will be operated in a reverse direction. I have shown the carriage B as provided with a funnel-shaped guide, B³, at one end, which passes over and receives the stirrup or stop E, and with a corresponding funnel-shaped guide, B⁴, at the other end, which receives a stop-hook, E². On the cam D² are 35 tocs or projections d⁵ d⁶, upon which the stirrup or stop E and the stirrup or hanger C⁶ operate as they enter their funnel-shaped guides 40 B³ B⁴.

The roadway A, as here represented, is inclined downward toward the position to which the carriage must go to be in hoisting position, and which is over the mine shaft or other 45 place from which weight is to be hoisted. While the hoisting-pulley C⁴ has no weight suspended from it, and when the hoisting-cable C is paid out, the hook D' is engaged with the stirrup or hanger C⁶ and prevents the 50 hoisting-pulley C⁴ from being lowered by such paying out thereof, and as fast as the cable C is unwound from the drum C³ the wheeled carriage B will travel along the roadway A toward the left of the drawings and until it 55 comes to the position shown in Fig. 2. While it is thus moving toward the left, the hook D is depressed out of operative position, as shown in Fig. 1, and the toe d⁶ upon the cam D² is protruded across the funnel-shaped guide B³. 60 As the carriage moves downward the funnel-shaped guide passes onto the stirrup or stop E, and by such stirrup or stop acting upon the cam-toe d⁶ the cam is swung from the position shown in Fig. 1 to that shown in Fig. 2. 65 By this movement of the cam D² the hook D is raised into engagement with the stirrup or stop E, as shown in Fig. 2, and the hook D' is

swung laterally out of engagement with the stirrup or hanger C⁶, and thereafter, as the hoisting-cable C is paid out, the hoisting-pulley C⁴ will be lowered into position for the desired weight to be attached to it. 70

As the cable C is wound up upon the drum C³ the hoisting-pulley C⁴ is raised, the cam D² being meanwhile in the position shown in Fig. 2, and as the stirrup or hanger C⁶ enters the funnel-shaped guide B³ it acts upon the cam-toe d⁶ and turns the cam to the position shown in Fig. 1. This movement of the cam swings the hook D' into engagement with the stirrup or hanger C⁶ and lowers the hook D out of engagement with the stirrup or stop E, and as the draft upon the hoisting-cable C continues the carriage B will be moved laterally along the roadway A until the draft upon the cable C ceases. 80

The hooked stop E² is placed on the roadway at the end of the traversing movement of the carriage, and as the carriage is moved along the funnel-shaped guide B⁴ passes over the hook E², and said hook is raised by and engages with a stirrup, E³, formed upon the end of a rod, E⁴, which is connected at e² with the cam D². As the funnel-shaped guide B⁴ passes over the hook E² the stirrup E³ is in the 95 position shown in Fig. 1; but as the winding up of the cable C ceases weight comes upon the hook E² and it pulls the stirrup E³ forward to the position shown in Fig. 2, and thereby turns the cam D² to the position shown in Fig. 2, 100 thus swinging the hook D' out of engagement with the stirrup or hanger C⁶ and permitting the hoisting-pulley and weight to be lowered, while the carriage is held against downward movement along the roadway by the hooked stop E². After the weight is deposited the winding-cable C is again drawn up, and the stirrup C⁶, entering the funnel-shaped guide B³, acts upon the cam D² and swings the hook D' into engagement with the stirrup or hanger C⁶, 110 thereby returning the cam D² to the position shown in Fig. 1. The hook E² and stirrup E³ constitute a retaining device for the carriage. 115

In Fig. 4 I have shown the hooked stop E² as pivoted at e² and as supported by disks or rotary heads e, swiveled upon the ends of a clamp, E⁴, as shown in Fig. 1, and by means of a downward-extending cord, e¹, the hook E² may be lifted out of engagement with the stirrup E³ when it is desired to release the carriage B and permit it to move downward to a hoisting position. The operator who controls the winding drum C³ should of course be signaled when the funnel-shaped guide B⁴ reaches the hooked stop E²; but in case he is not thus signaled or does not properly respond to such signal the stirrup E³ would soon reach the shoulder e² upon the hook E², or the funnel-shaped guide would strike against the parts supporting said hook and cause breakage. To 125 prevent this the hook E² may, if desired, be pivoted at e² in a slide, e⁶, mounted on the roadway A, as shown in Fig. 1, and may be connected by a cord, e⁷, with the heads or disks 130

e, which constitute the support for holding the hook with the carriage engaged with it. This rope or flexible connection e' permits the slide e⁶ to be moved back readily for a considerable 5 distance in case the carriage B comes in contact with it. If, however, the person controlling the hoisting-drum C³ is properly signaled and properly responds to his signals, the arrangement shown in Fig. 4 is all that is necessary and may be relied on without the employment of the slide e⁶ and the cord or flexible connection e'.

As best shown in Fig. 3, there are in opposite sides of the funnel-like guide B³ inclined 15 flanges b', which bear upon the stirrup or stop E as the said guide passes onto the stirrup or stop, and thus hold said stirrup down for the hook D to properly engage with it.

From the above description it will be understood 20 that the operation of the apparatus in changing from hoisting to traversing and from traversing to lowering at the mouth of a mine-shaft or other place where the hoisting is solely performed is automatic. As the wheeled carriage B is returning to the hoisting position the cam D² is operated to unlock the stirrup or hanger C⁶ from the carriage and to lock the carriage to the stirrup or stop E, and the further paying out of the cable C lowers the hoisting-pulley C⁴. As the hoisting is completed the stirrup or hanger C⁶ enters the funnel-shaped guide B² and operates the cam D² to unlock the hook D from the stirrup or stop E and to lock the hook D' upon the stirrup or hanger C⁶.

35 From the above description it will be understood that the cable C constitutes both a hoisting and a traversing cable, and that the hooks D E², with the stirrups E E³, constitute locks, whereby the carriage B is held at opposite ends of its traversing movement. The hook D' also constitutes a lock for holding the hoisting-pulley C⁴ suspended independently of the cable C.

40 As shown, the pins d³ d⁵, whereby the hooks D D' are connected with the cam D², are nearly or quite in lines drawn between the pivot d² of the cam and the shoulders of the hooks, and hence a pressure against the hooks transversely to their length has no tendency to turn the 45 cam and disengage the hooks.

What I claim as my invention, and desire to secure by Letters Patent, is—

1. The combination, with a wheeled carriage and a suspended roadway therefor, of a hoisting-pulley, a hoisting and traversing cable passing over a pulley on the carriage and having a bight depending from the carriage and in which the hoisting-pulley is hung, a frame for said hoisting-pulley, a hoisting-drum for 55 taking up the said cable, a hook pivoted upon the carriage, a stop upon the roadway with which said hook engages to hold the carriage in hoisting position, and a rotary cam independent of said hook pivoted on the carriage 60 and having a curved slot with which said hook engages, said cam being rotated by the hoisting-pulley frame during the upward movement

of the latter to free said hook from the stop and permit the carriage to be traversed by a draft upon the said cable, substantially as herein described. 70

2. The combination, with a wheeled carriage and an elevated roadway therefor, of a hoisting-pulley, a hoisting and traversing cable passing over a pulley on the carriage and 75 having a bight depending from the carriage and in which the hoisting-pulley is hung, a hoisting-drum for taking up the said cable, a stirrup rising from the hoisting-pulley frame, a hook pivoted upon the carriage for engaging with said stirrup when the hoisting-pulley occupies an elevated position, and a cam independent of said hook, having a curved surface against which said hook bears and which is rotated by the stirrup in rising to 85 swing said hook into engagement with said stirrup, substantially as herein described. 80

3. The combination, with a wheeled carriage and an elevated roadway therefor, of a hoisting and traversing cable passing over a 90 pulley on the carriage and having a hoisting-pulley hung in a bight of the cable, a frame for said hoisting-pulley, a hoisting-drum for winding up the cable, a hook pivoted upon the carriage for securing the carriage on the 95 roadway in hoisting position, a stop upon the roadway with which said hook engages, a second hook pivoted upon the carriage for holding the hoisting-pulley suspended independently of the said cable, a stirrup on said hoisting-pulley frame for engaging the second-named hook, and a rotary cam independent 100 of said hooks mounted on said carriage and provided with curved surfaces against which said hooks bear, said cam being rotated by the 105 hoisting-pulley frame while rising to simultaneously release the first-named hook from the catch and to swing the second-named hook into engagement with said stirrup, substantially as herein described. 110

4. The combination, with a wheeled carriage and an elevated roadway therefor, of a hoisting and traversing cable passing over a pulley on the carriage and hanging in a bight therefrom, a hoisting-pulley hanging in said 115 bight, a stirrup rising from the hoisting-pulley frame, a hoisting drum for operating the cable, a hook on the carriage for engaging said stirrup to hold the hoisting-pulley independently of said cable, a retaining device for holding the carriage fixed on the roadway at the end of one of its traversing movements, the member of said retaining device which is on the carriage being longitudinally movable, and a rotary cam with which said longitudinally-movable member of the retaining device is connected, said cam being provided with a curved surface against which said hook bears, the longitudinally-movable part of the retaining device operating when moved in one direction to rotate said cam to release said hook from the stirrup, substantially as herein described. 120 125 130

5. The combination, with the wheeled car-

riage, its elevated roadway, the hoisting and traversing cable depending in a bight from the carriage, and the hoisting-drum, of the hooks D D', the cam D², for operating said hooks, and provided with toes d⁹ d¹⁰, the hoisting-pulley C¹ and its frame C⁵, having the upwardly-projecting hanger or stirrup C⁶, and the stirrup or stop E upon the roadway, substantially as herein described.

10 6. The combination, with the wheeled carriage and its elevated roadway, the hoisting and traversing cable depending in a bight from the carriage, and the hoisting-drum, of the hooks D D', the cam D², for operating said hooks, and provided with toes d⁹ d¹⁰, the hoist-

ing-pulley C¹ and its frame, provided with the upwardly projecting stirrup or hanger C⁶, the stirrup E on the roadway, for engagement with the hook D to lock the carriage in hoisting position, and the lock for holding the carriage at the opposite end of its traversing movement, the member E³ of said lock which is on the carriage having a limited sliding movement and being connected with the cam D², substantially as herein described.

NORMAN C. HARRIS.
